UNITED STATES PATENT OFFICE.

ALBERT J. LINDEMANN, OF MILWAUKEE, WISCONSIN.

DESIGN FOR A STOVE.

48,118.

Specification for Design.

Patented Nov. 9, 1915.

Application filed June 8, 1915. Serial No. 32,973. Term of patent 7 years.

To all whom it may concern:

Be it known that I, **ALBERT J. LINDEMANN**, a citizen of the United States of America, and a resident of the city of Milwaukee, county of Milwaukee, State of Wisconsin, have invented a certain new, original, and ornamental Design for a Stove, of which the following is a specification.

In the accompanying drawing, the figure

is a perspective of a stove illustrating the design.

I claim:

The ornamental design for a stove as shown.

ALBERT J. LINDEMANN.
